UNITED STATES PATENT OFFICE

2,454,497

ELECTRICAL APPARATUS

Howard W. Ashton, Havertown, Pa., assignor to
 Oliver W. Storey, Chicago, Ill., as trustee for
 the partnership of O. W. Storey & Associates,
 Chicago, Ill.

Application August 8, 1947, Serial No. 767,507

10 Claims. (Cl. 171—330)

1

This invention relates to an electrical apparatus and particularly to a capillary electrometer type of transducer. As is well known, a capillary electrometer type of transducer comprises an insulating container including a capillary portion, said container having at least two substances in liquid or liquid-like form to provide at least one or more interfaces. An example of two substances in common use for providing interfaces is mercury and sulphuric acid. Other materials, such as gallium, may be substituted for mercury; and a large number of materials, both organic and inorganic, are known for possible substitution for sulphuric acid. While the invention will be described in connection with a mercury-sulphuric acid couple, it will be understood that the invention has general application to capillary electrometer transducers irrespective of the nature of the interface-forming materials.

In any capillary electrometer type of transducer, there will generally be insulating material such as glass, a liquid or liquids such as mercury, a gas or vapor, and a solid conducting material, such as platinum, for electrical connection. It has been found that, in many types of transducer constructions, failure in some instances may be due to gas or vapor working along solids and in the liquid to finally become entrained in the interface-forming liquids. In particular, in a sealed type of capillary electrometer transducer, such as disclosed and claimed in the copending application of William H. Bussey, S. N. 573,968, filed January 22, 1945 now Patent 2,431,367, issued November 25, 1947, and Howard W. Ashton, S. N. 740,419, filed April 19, 1947, it is a practical impossibility to avoid having some gas or vapor in the system. Where the enclosing material is glass, it is necessary to rely on gas or vapor for taking up the displacement of the liquid columns incident to electrometer operation.

In some instances, the amount of gas or vapor, at one or both ends of the capillary system, may be microscopic. Nevertheless, such gas or vapor does exist and, by controlling the amount and pressure thereof, substantial control over the vibration characteristics of the system may be exercised. In some instances, the gas or vapor may be the same material used in liquid form in the electrometer transducer.

Thus, it is evident that, in a sealed system containing mercury and sulphuric acid diluted with water, for example, it will not be possible to have an evacuated region under normal temperatures. Therefore, unless some gas such as

2

air or nitrogen or any other gas is introduced, there will be mercury and water in gaseous phase existing under operating conditions. Even in the case of air or any other gas which is introduced, there is undoubtedly some component of mercury and water vapor present. However, the pressure of such gas or vapor may be varied over substantial limits. Thus, the lower limit will be the vapor pressure of the sulphuric acid solution and mercury at the operating temperature of the transducer. The upper limit may be determined by the strength of the glass. In practice, variations in pressure from the order of a fraction of a millimeter at the lower end up to several atmospheres are readily possible.

The problem solved by this invention is the maintenance of gas or vapor in predetermined regions of a capillary electrometer transducer system and the prevention of migration of such gas or vapor from its desired location to an undesired location in the capillary channel interfaces. While this invention is particularly concerned with a sealed capillary electrometer transducer, it is equally applicable to an open-type system.

Inasmuch as such capillary electrometer transducers are generally constructed of tubing, such as glass for example, and since at least one of the current leads is preferably sealed in at one end, it has been found that special construction for such lead-in is required at the gas chamber end of the system. A conventional wire lead-in passing through the gas chamber into the mercury-containing chamber generally has long length, compared to stiffness, so that the wire may be bent to one side and lie against the glass. It has been found that better contact between wire and mercury is obtained if the wire is clear of the glass and dips into the mercury. By virtue of the invention herein, a lead-in construction is provided, which cooperates with a constricted channel connecting the gas chamber and mercury-containing chamber, to provide a desirable and satisfactory lead-in.

In order that the invention may be understood, it will now be explained in connection with the drawings wherein exemplary embodiments are shown. Referring to the drawing, Figure 1 shows a capillary electrometer transducer embodying the present invention. Figure 2 shows a different type of capillary electrometer transducer including a Bourdon tube also embodying the present invention. Figure 3 illustrates one manner of making a structure embodying the present invention.

Referring first to Figure 1, a capillary electrometer type of transducer, described and claimed in the copending application of Howard W. Ashton referred to before is shown. In this figure, glass tube 10 has capillary channel 11 therein terminating in enlarged regions or chambers 12 and 13. Region 13 is connected by constriction 14 to chamber 15, which may be evacuated or contain gas or vapor. Tube 10 has sealed end 16 in which is disposed wire lead 17. Wire lead 17 passes from the exterior to the interior of the tubular system. Wire lead 17 extends through chamber 15 and has portion 18 in kinked or coiled form disposed in constriction 14. The lead continues as portion 19 in the form of a straight conductor into region 13. The lead may be of platinum or other conductor inert to mercury and sulphuric acid or whatever liquids are used for forming an interface or for forming a conducting medium between the wire lead and interface-forming liquids.

Disposed within enlarged regions 12 and 13 are bodies of mercury. Within capillary channel 11 are globules of mercury and other interface-forming electrolyte, such as sulphuric acid diluted with water to a concentration of the order of between ten and forty percent. Other interface-forming liquids may be used as desired.

Capillary bore 11 may have a diameter of between about .002" and .015" though other dimensions may be used and may have any desired length, such as about .3" although other bore diameters and lengths may be used. Enlarged regions 13 and 15 may have transverse dimensions of about .025" and .050" respectively, and may have a length of about .2".

Constriction 14 is preferably short and preferably has a substantially larger diameter than capillary channel 11. In practice, constriction 14 may have a diameter of about twice that of capillary 11, thus giving the constriction about four times the cross-sectional area. With a capillary bore of about .006", a constriction diameter of about .015" has been found satisfactory for use in a transducer for phonograph records.

The mercury or other liquid must fill chamber 13 and preferably extends at least part way into constriction 14. Thus, chamber 13 will be free of gas or vapor. Since the operation of a transducer depends upon displacement of the interfaces and liquid, it will be evident that some freedom for movement of the liquid surface must be provided. If the cross-sectional area of constriction 14 is too small, the resistance to liquid movement will be excessive and will have well-defined effects on the over-all vibration response characteristics of the transducer system. However, if the liquid is to be retained in chamber 13 by capillary force, it is essential that the cross-sectional area of constriction 14 be small enough to provide the desired and necessary capillary force.

It is, of course, possible to have gas or vapor under pressure within chamber 15 for controlling the vibration-response characteristics of the entire system. In such case, it is essential that the resistance to liquid and gas movement through constriction 14 be small.

By analogy to electrical circuits, constriction 14 may be considered as a coupling means having a certain amount of resistance. Obviously, if a coupling element in an electrical circuit has excessive resistance, the resonance characteristics of the system as a whole may be eliminated,

Assuming that resonance characteristics are desired in this transducer, the control of the volume of chamber 15 and the pressure of the gas therein, as well as the cross-sectional area and length of constriction 14, will result in a substantial control of the resonance and frequency-response characteristics of the entire system as a whole.

Constriction 14 may be small enough so that the mercury will be retained in position by capillary force independently of the kinked portion of the lead. However, where peculiar conditions require, constriction 14 may be made to have substantial length and substantial cross-sectional area. In such case, having the wire break the area up into numerous small areas will greatly increase the capillary force existing at the surface of the mercury. The resistance to flow of gas or liquid may, however, be kept quite low if desired.

Capillary bore 11 and enlarged regions 12 and 13, as well as constriction 14 and chamber 15, are most conveniently formed in circular cross section although other configurations are possible. It is preferred to dimension chamber 13 so that its volume is small as possible consistent with good mechanical construction.

Sealed in the wall of tube 10 is lead 20 having portion 21 extending within region 12. As shown here, tube 10, adjacent region 12, flares to provide annular portion 25. This portion may have substantial thickness and rigidity. Carried by portion 25 at the edge thereof is diaphragm 27, the diaphragm being joined to portion 25 at annular flexing region 28. Diaphragm 27 is most conveniently formed of glass, as is tube 10, and is fused to portion 25. Annular flexing region 28, where the two portions unite, is preferably thin and is endowed with substantial flexibility. It is preferred to have diaphragm 27 quite rigid, although this may be thin and relatively flexible if desired.

Region 30, within annular portion 28 and between diaphragm 27 and portion 25, is filled with liquid, such as mercury. If desired, a chamber similar to 15 may be provided in communication with regions 12 or 30. Such additional chamber might contain a gas or vapor at a suitable pressure as desired. However, some gas or vapor will be present or may be introduced usually at some part of region 28.

Referring now to bent portion 18 of the wire lead, it will be evident that, if this wire is pre-formed so that lead portion 19 extends forwardly of bent portion 18, lead portion 19 will lie within the center of region 13.

Referring now to Figure 2, a capillary electrometer and Bourdon tube transducer system embodying the present invention is disclosed. The combination of a capillary electrometer and Bourdon tube is disclosed and claimed in the application of William H. Bussey, referred to before.

Referring now to Figure 2, capillary electrometer portion 10' has capillary channel 11' with chambers 12' and 13' at the two ends. Chamber 12' forms part of a Bourdon tube system with bight portion 32 bent in a generally U shape and having a generally oval cross section. Bight portion 32 has end portion 33 connected thereto and terminating in seal 34. Sealed in portion 34 is lead 35 of any suitable wire, such as platinum, this lead having eye 36 formed therein and extending into the region formed by end portion 33.

As is well understood, capillary portion 11' has

interface-forming liquids, such as mercury and sulphuric acid, while chamber 12' and the rest of the Bourdon tube system is sealed with a liquid having suitable electrical conductivity, such as mercury for example. Chamber 13' is also filled with a conducting liquid such as mercury. The entire system may be formed of glass in a manner to be explained in connection with the description of Figure 3.

Chamber 13' is connected by constriction 14' to gas chamber 15'. Gas chamber 15' is sealed by a mass of glass 16' and has lead wire 17' passing through seal 16' and through chamber 15'. Lead wire 17' is coiled or kinked at 18' and has portion 18' extending into chamber 13'. Coiled or kinked portion 18' of the lead wire is so shaped with relation to the transverse dimension of constriction 14' as to permit portion 18' to bear against the entrance to constriction 14' as shown. Both in Figures 1 and 2, it is preferred to have the wire so shaped as to break up the space within or adjacent the constriction into fine capillary spaces whereby large capillary forces are present for retaining mercury or other liquid in chamber 13'.

Some gas or vapor is present at region 33. In many instances, the amount is so small that the bubble cannot be seen with the unaided eye. Its presence may be indicated, however, by evacuating chamber 15' and disposing the entire liquid system as to permit the microscopic gas bubble to expand. No attempt has been made to show the gas at region 33 in proper volumetric proportion.

It will be noted that any gas or vapor at region 33 represents compliance and in combination with the constants of the remainder of the system will control the frequency response characteristic of the system. For use in phonographs, it is preferred to have some gas at 33.

In combination with restricted opening 14', coiled part 18' of the lead functions to retain liquid in chamber 13' through capillarity. Resistance to vibratory energy transfer is also introduced, and this may be predetermined for the purpose of controlling resonance peaks.

Referring now to Figure 3, blanks for making the capillary electrometer of Figure 2 are shown. Thus, tubular system 50 is fabricated to provide the same with the capillary chambers and Bourdon tube portion described above in connection with Figure 2. Region 33 of the blank has restricted portion 51, this portion continuing thereafter as tubular channel 52. Lead 35, having eye 36, has formed thereon glass bead 53. This lead and bead assembly is disposed within the tubular system, it being understood that bead 53 is just small enough to enter into constriction 51. The bead and constriction are melted together in a flame.

Lead 17', having performed portion 18' and straight portion 19', has glass bead 55 formed thereon. Glass bead 55 is formed at a suitable portion on lead 17' so that the bead will be spaced at a predetermined distance corresponding to seal 16'. Blank 50 itself has chamber 15' provided with restriction 56. Thus, lead 17' and the bead may be inserted.

Gas chamber 15 in both structures may be provided with gas or vapor at any desired pressure during the process of manufacture. In addition, the pressure and volume of gas at the other end of the tubular system, this being in chamber 30 of Figure 1 and in annular region 33 of Figure 2, may also be controlled. By controlling the length and transverse dimension of constriction 14', the

thickness and character of the glass, it is possible to endow the system with any desired frequency response. Thus, the device as a whole has within it inertia due to liquid, elasticity due to compression of gas or vapor as well as flexure of glass, and resistance due to the constricted nature of the sum of the channels. By proper control of these elements, the entire transducer may be endowed with characteristics which will remain constant over the useful life of the device.

In addition to the above, the disposition of the kinked lead in the manner shown provides for good contact between the wire and mercury under all conditions.

What is claimed is:

1. A capillary electrometer transducer comprising an insulating container having two chambers therein connected by a capillary channel, interface-forming liquids in said capillary channel providing at least one interface in said channel, conducting liquids in said chambers for providing electrical connections to said interface-forming liquids, said container having a third chamber connected to one of said two chambers by a restricted channel with the liquid in said one chamber

25 extending at least partly into said restricted channel, wire leads extending from the exterior of the capillary system to the liquid-filled chambers, one of said wires having a portion disposed in said third chamber, said one wire extending through said restricted channel into the liquid in said one chamber.

2. The structure of claim 1 wherein said other chamber contains gas at a predetermined pressure to provide compliance to the system.

3. The structure of claim 1 wherein said wire has a bent portion at said restricted channel shaped to fit against the channel wall.

4. A capillary electrometer transducer comprising an insulating container having a pair of chambers connected by a capillary channel, said two chambers and capillary channel having liquids therein with said capillary channel having at least one interface therein, one of said chambers having a restricted opening at a part remote from said capillary channel, said insulating container having a third chamber aligned with said one chamber and connected thereto through said restricted opening, wire leads sealed in said container walls for said liquids, said one chamber having the liquid therein extending into said restricted opening, one wire lead passing through said third chamber and through said restricted opening into said one chamber for making contact

50 with the liquid therein, said wire lead having the portion thereof at said restricted opening shaped so that the wire may fit snugly against said restricted opening, the portion of said wire extending into said one chamber being spaced from the 55 container walls.

5. The structure according to claim 4 wherein said insulating container is sealed, one seal being at said third chamber with the wire passing through from the interior of said third chamber to the exterior of the insulating container.

6. The structure according to claim 4 wherein said restricted opening has a transverse dimension of capillary dimensions to prevent migration of gas into said one chamber.

7. The structure according to claim 4 wherein said third chamber is sealed to atmosphere and contains gas at a predetermined pressure and wherein said restricted opening and wire lead cooperate to prevent gas migration into said one 75 chamber.

8. A capillary electrometer comprising an insulating container having three chambers connected in series by two capillary channels, liquids in two adjacent chambers and one capillary and forming at least one interface within said capillary for electrometer operation, wire leads sealed in said container and making contact respectively with the liquids in said adjacent chambers, the wire lead for the middle chamber passing through the second capillary and through said third chamber, said middle chamber being filled with liquid and the liquid extending at least partly into said second capillary channel, said second capillary channel having a transverse dimension substantially greater than the diameter of said last-named wire lead, said last-named wire lead having the portion passing through said second capillary deformed so that the wire may be sprung into and retained by the wall of said second capillary, the liquid contacting portion of said wire extending from said second capillary clear of the container wall.

9. A capillary electrometer transducer comprising an insulating container having two chambers connected together by a capillary channel, liquids filling said chambers and channel for forming at least one interface in said channel, one of said chambers having a restricted opening at a part remote from said capillary channel, said

insulating container having a third chamber aligned with said one chamber and connected thereto through said restricted opening, wire leads for said liquids sealed in the container walls, said one chamber having the liquid therein extending into said restricted opening so that said one chamber is completely filled with liquid, one of said wire leads passing through said restricted opening into said one chamber for making contact with the liquid therein, said third chamber being substantially free of liquid and having gas therein, the other of said pair of chambers containing gas at a region removed from the capillary channel connecting it with said one chamber, said gas regions, liquids and elasticity of container cooperating to endow the system with predetermined elasticity and mass and thereby determine the frequency response characteristic of the transducer.

10. The structure of claim 9 wherein said wire lead has the portion thereof at said restricted opening coiled so that the wire may fit snugly against the container wall at said restricted opening, said wire coil and restricted opening providing predetermined resistance for transmission of vibratory energy.
